PILOT CONTROLS FOR PNEUMATIC CABLE-TOOL DRILLS

Johann Hans Meier, South Milwaukee, Wis., assignor to Bucyrus-Erie Company, South Milwaukee, Wis., a corporation of Delaware

Application January 25, 1952, Serial No. 268,301

8 Claims. (Cl. 255—10)

This invention relates to new and useful improvements in operating controls for pneumatic-type cable-tool drills.

In such drills a rope passes from a winch drum on the main frame, around a sheave at or near the rear end of the machine, thence under another sheave at or near the front end of the machine behind the foot of a mast, thence over a crown sheave near the upper end of the mast, and thence downward into the hole which is being drilled in the ground. At the lower end of this rope is a string of percussion drilling tools, terminating in a bit. The drilling tools at the end of the rope are reciprocated up and down by oscillation of cable-engaging means, such as a crown sheave, which is slidably mounted in the mast and is actuated by a pneumatic cylinder-piston assembly.

The principal objects of my invention are to provide a pilot system for controlling the intake and exhaust of air (or gas) to and from the piston chamber such that

(1) The intake and exhaust valve system of the cylinder-piston assembly has only two controls, both depending, through novel interlocked pilot means, on the motion of the piston.

(2) The controls are greatly simplified by using the position of the exhaust valve as a partial pilot means for actuating the intake valve.

(3) Cycle time is reduced by automatically exhausting air from the cylinder chamber before the piston reaches the top of the tool-lifting stroke, thus eliminating the last, inefficient part of the expansion portion of the cycle.

(4) Fast response of the intake and exhaust valves is obtained.

(5) The controls are simple and inexpensive to build and operate.

In addition to the principal objects, above stated, a number of novel and useful details have been worked out which will be readily evident as the description progresses.

The invention consists in the novel parts and in the combination and arrangement thereof, which are defined in the appended claims, and of which two embodiments are exemplified in the accompanying drawings which are hereinafter particularly described and explained.

Figure 1 is a side elevation of a drill embodying the invention.

Figure 2 is an enlarged partly schematic representation of the cylinder-piston assembly, the intake and exhaust valves therefor, and the air-pilot controls for said valves, together with the closed pneumatic circuit connecting such elements to each other and to the receivers and air compressor.

Figure 3 is an enlarged vertical sectional view of the intake valve.

Figure 4 is an enlarged vertical section, similar to Figure 3, but showing the exhaust valve and its associated air-pilot means for controlling the intake valve.

Figure 5 is a bar chart showing the air-pressure in

2

the main cylinder chamber and the operation of the air-pilot control valves, the exhaust valve, and the intake valve for various positions of the main piston in its operating cycle.

5 Figure 6 is an enlarged partly schematic representation of the cylinder-piston assembly, the intake and exhaust valves therefor, and a second embodiment of the pilot controls for said valves, together with their electrical circuit.

10 Turning now to Figure 1, we see that 11 is the main frame of a drill, supported by creeping traction 12.

The frame 11 supports a mast 14 (called a "derrick" in the art), a motor 15, a winch 16, a main air compressor 17, and associated driving connections (not numbered).

15 From the winch 16, a rope 18 runs around spooling sheave 19, thence under fairlead sheave 20, thence over crown sheave 21 at the top of the mast 14, thence down to the tools 22. Crown sheave 21 rotates about pin 23 mounted in a crown-sheave frame 24 which is slidably mounted for vertical movement within the upper section 25a of the mast and is connected to the end of piston rod 26 of cylinder-piston assembly 27. Crown sheave 21, with its actuating cylinder-piston assembly 27, constitutes a cable-engaging spudding means for imparting vertical reciprocating motion to the drilling tools 22.

20 Turning to Figure 2, cylinder-piston assembly 27 consists of cylinder 28 mounted within section 25b of mast 14, and main piston 29 to which rod 26 is connected.

25 The cylinder-piston assembly 27 is single-acting, the pressure chamber 30 being located below the piston 29.

The air in the pressure chamber 30 is controlled through intake valve 32 and exhaust valve 33. Air pressure is supplied to intake valve 32 through main supply line 35 from the high-pressure receiver 36 which in turn is supplied with air pressure by the air compressor 17 through line 37.

30 Exhaust air is conducted from exhaust valve 33 through main exhaust line 39 to low-pressure receiver 40, pressure in which is maintained by auxiliary air compressor 41.

35 Low-pressure receiver 40 is in turn connected through main supply line 42 to the intake of main air compressor 17. Thus it is seen that the air system for actuating cylinder-piston assembly 27 is a "closed" system. Upper chamber 31 of cylinder-piston

40 assembly 27 is maintained normally at atmospheric pressure by vent 34. The area of this vent is preferably restricted to permit throttling or bumper action if main piston 29 overspeeds because of too light tools or breakage of the tool line. To dissipate the energy of the tools when dropping freely from full stroke without striking the bottom of the well, a shock absorber or resilient bumper 38 is preferably employed at the lower end of and inside the cylinder 28.

45 The intake valve 32 and the exhaust valve 33 are controlled by the following described automatic air-pilot control mechanism to which the invention is principally directed.

In Figure 2, the air-pilot control lines are indicated by single lines (either full or broken) in order to distinguish them from the double lines that indicate the main lines of the above-described closed circuit for supplying air to the cylinder-piston assembly 27.

50 To clarify the air-pilot control circuit, the following conventional single lines are used. A single full line represents a pilot line that is always under high pressure. A single line of dashes indicates a line that is under either high or low pressure depending on the positions of the manual control and air-pilot valves. A single line of dots and dashes indicates a pilot line that is always under low pressure.

55 The supply of air pressure to the air-pilot control sys-

tem is controlled by manual control valve A. Air under pressure is supplied to this valve from high-pressure receiver 36 by line 50 to intake port 51 on valve A. When the plunger 54 of main-control valve A is in raised or "open" ("high pressure") position, as shown in Figure 2, air under pressure flows through port 51, annular recess 55, center port 52, and high-low pressure line 56 to intake port 61 of intake-cutoff-control air-pilot valve B and to intake port 71 of exhaust-cut-off-control air-pilot valve C. When the plunger 54 of valve A is in lowered "closed" position (not shown) it blocks off intake port 51 and connects center port 52 to exhaust port 53 through annular recess 55, port 53 being connected by low-pressure line 57 to the low-pressure receiver 40.

The plunger 54 of manual-control valve A is actuated, through link 46, by operating lever 44 which is pivotally mounted on fulcrum 45 located preferably near the base of the machine.

Main-control valve A controls supply of pressure fluid through line 56 to intake-cutoff-control air-pilot valve B and to exhaust-cutoff control air-pilot valve C, both of which valves are actuated by cam 58 on piston rod 26.

Intake-cutoff air-pilot valve B is the principal piloting means for controlling the intake valve 32. It is actuated by cam surface 58a of cam 58, which bears against roller 60 mounted on the end of plunger 64. At the start of the up-stroke of the main piston assembly 29, roller 60 bears against the upper portion 58a' of cam surface 58a, so that the plunger 64 is in "open" position (shown in Figure 2). In this position, air under pressure from port 52 of main-control valve A flows through line 56 to intake port 61 of valve B, thence through annular recess 65, center port 62, and line 66 to intake port 81 of air-pilot valve D on exhaust valve 33, and thence through valve D to intake valve 32 as will be described hereinafter. When the main piston 29 rises to the upper portion of its stroke, roller 60 bears against the lower portion 58a" of cam surface 58a, so that plunger 64 of valve B is advanced by spring 68 into "cut-off" position. In this position, port 61 is blocked off by plunger 64, and ports 62 and 63 are interconnected through recess 65; so that line 66 as well as the recess 65 itself is connected through line 67 to low-pressure receiver 40. In this way, any leakage in either air-pilot valve B or air-pilot valve D is conveyed to the low-pressure receiver, and compressed air in the pilot system beyond line 66 is drained off causing intake valve 32 to close.

In order to vary the length of stroke of the main piston 29, by varying the cutoff point at which valve B cuts off air pressure actuating intake valve 32, air-pilot valve B is slidably mounted on mast 14, so that its vertical position can be varied at will by operating lever 44 which is connected to valve B by link 69. This arrangement permits the operator to gradually increase the length of the main piston stroke as he starts the machine by opening main-control valve A. In this way the machine can be started smoothly, and the number of operating controls is reduced to a minimum.

Exhaust-cutoff air-pilot valve C is the piloting means for controlling the exhaust valve 33. It is actuated by cam surface 58b of cam 58, which bears against roller 70 mounted on the end of plunger 74. At the bottom of the stroke of the main piston 29, roller 70 bears against the upper portion 58b' of cam surface 58b, so that the plunger 74 is advanced to "open" position. In this position, air under pressure from port 52 of main control valve A can flow through line 56 to intake port 71 of valve C, and thence through annular recess 75, center port 72, and line 76 to port 91 of actuating chamber 93 of exhaust valve 33. When the main piston 29 rises above its "near-bottom" position to the position shown in Figure 2, roller 70 bears against the lower portion 58b" of cam surface 58b, so that plunger 74 of air-pilot valve C is returned to "cut-off position" against spring 78. In this position, port 71 is blocked off by plunger 74, and ports 72 and

73 are interconnected through recess 75, so that line 76, as well as recess 75, is connected through line 77 to low-pressure receiver 40. In this way any leakage into valve C is conveyed to the low-pressure receiver 40.

Turning now to Figure 4, which is an enlarged view of exhaust valve 33 and air-pilot control valve D, it will be seen that the exhaust valve is preferably a spring-opened, air-pilot closed valve, in order to drain any leakage air from main cylinder chamber 30 to low pressure receiver 40 when machine is at rest. Pilot-air pressure admitted through line 76 (Figure 2) and port 91 to actuating chamber 93 acts against the lower face of plunger 84 and lifts the plunger with stem 94, thus compressing spring 98 and pressing valve discs 95a and 95b against their seats 96a and 96b, respectively, and so closing exhaust valve 33. Valve disc 95b is larger than valve disc 95a, and hence any air pressure in main cylinder chamber 30 imposes a net force on the valve discs, such force tending to keep exhaust valve 33 closed. As long as this net force is greater than the reaction of compressed spring 98, the valve 33 stays closed, regardless of the pilot-air pressure in actuating chamber 93. Therefore, even if pilot-air pressure is drained from actuating chamber 93 once closed, exhaust valve 33 stays closed until the air-pressure in main cylinder chamber 30 drops below the air pressure required to balance the reaction (pre-determined by adjusting screws 99) of spring 98; and once open, exhaust valve 33 stays open until pilot-air pressure is admitted to actuating chamber 93. Any leakage air in the compartment for spring 98 is drained to the low-pressure line 39 by axial passage 92 in valve stem 94.

Air-pilot valve D is the auxiliary piloting means for controlling the intake valve 32. Plunger 84 of air-pilot valve D is integral with stem 94 of exhaust valve 33. When exhaust valve 33 is in its open position, pilot-air pressure at intake port 81 of air-pilot valve D is blocked by plunger 84, and center port 82 is connected to exhaust port 83 through annular recess 85 in plunger 84. When exhaust valve 33 is in its closed position, intake port 81 of air-pilot valve D is connected to center port 82 through annular recess 85 of plunger 84, and exhaust port 83 is blocked.

Turning to Figure 3, which is an enlarged view of intake valve 32 and its actuating piston 104, it will be seen that this valve is preferably a spring-closed pilot-air-opened valve, in order to permit building up air pressure at the start of the drilling operation. To open the valve, pilot-air pressure is admitted to port 101 into chamber 103 and acts against piston 104 to push the same downwardly against the valve-closing compression spring 108; and thus opens valve discs 105a and 105b which are seated against seats 106a and 106b respectively when the intake valve 32 is in closed position. Any leakage air below piston 104 is exhausted through port 102 and line 57 to low-pressure receiver 40.

As shown in Figure 2, center port 62 of air-pilot valve B is connected through line 66 to intake port 81 of air-pilot valve D and center port 82 of air-pilot valve D is connected through line 86 to intake port 101 and actuating chamber 103 of intake valve 32. Exhaust port 83 of air-pilot valve D is connected to low-pressure receiver 40 through line 77. Thus, it is seen that the net effect of air-pilot valve B and air-pilot valve D (which are connected in series) on control of the intake valve 32 is that the intake valve 32 is closed automatically by its spring 108 whenever pilot air pressure leading into its chamber 103 is cut off and drained by pilot valve B; when the main piston 29 is above a selected cut-off point determined by the relative position of pilot valve B and cam 58. When main piston 29 is below this predetermined cutoff point, pilot valve B admits pilot air pressure to pilot valve D; if then the exhaust valve 33 is closed (during upstroke), pilot valve D transmits this pilot air pressure to intake valve 32 thereby holding the same open; but if, however, the exhaust valve 33 is open (during downstroke), valve D

blocks pilot air pressure off from the intake valve 32 thereby holding the same closed.

The operating cycle of the above-described apparatus, starting from rest at the bottom of the stroke, is as follows:

(1) *Bottom rest position.*—Piston 29 is at the bottom of its stroke. Main-control valve A is in closed position, so that its port 51 is blocked off and there is no pressure in the entire pilot-air system. Pilot valves B and C are in open position, their ports 61 and 71 respectively being open, but pilot valve D is closed, its port 81 being blocked off, since exhaust valve 33 is held open by its spring 98. Accordingly the intake valve 32 is held closed by its spring 108 and the differential action of valve discs 105a and 105b, and the air in chamber 30 of the cylinder-piston assembly is at the low pressure of the low-pressure receiver 40.

(2) *Start (upward).*—Piston 29 is still at the bottom of its stroke, but main-control valve A is now open, and, since pilot valves B and C are also open, air pressure through port 91 of pilot valve D lifts plunger 84, so that exhaust valve 33 is closed and at the same time port 81 of pilot valve D is uncovered permitting air pressure to flow through line 86 to actuating chamber 103 of intake valve 32, thereby opening it and causing pressure to build up in chamber 30, which in turn starts upward motion of main piston 29.

(3) *Early upstroke (see Figure 2).*—In this position of the upstroke main piston 29 is above its "near-bottom" position, but below its cutoff position. As in starting position, main-control valve A and pilot valve B are open, but pilot valve C is now closed, since its plunger 74 has now been returned to closed position by the lower portion 58b' of cam 58b. Hence air pressure in actuating chamber 93 (Figure 4) of exhaust valve 33 is now low instead of high, but, in spite of this, exhaust valve 33 remains closed and pilot valve D remains open because of the high pressure in the main cylinder chamber 30. Accordingly the exhaust valve remains closed and the intake valve remains open as in the previous position.

(4) *Mid upstroke.*—In this position, the piston 29 is just above its cutoff position. Main-control valve A remains open. But, since the roller 60 of pilot valve B has now passed the cutoff point on cam 58a, port 61 is blocked off and actuating chamber 103 of intake valve 32 is now connected, through pilot valves D and B, to low-pressure receiver 40, so that intake valve 32 automatically closes. Exhaust valve 33 remains closed due to internal pressure in the main cylinder chamber 30.

(5) *Late upstroke.*—Piston 29 is now near the top of its stroke. Due to air expansion, pressure in the now sealed off main cylinder chamber 30 drops below the preset value necessary to hold the exhaust valve closed. Accordingly the exhaust valve 33 opens and the pressure in the cylinder chamber 30 drops to the low pressure of tank 40. Pilot valve D also closes, but this does not affect the intake valve, because pilot air pressure to the intake valve is already cut off and drained by pilot valve B.

(6) *Top and early downstroke.*—In this portion of the cycle, the piston is at the top of its stroke and above intake cutoff in its downstroke, the fall of main piston 29 being checked by the low pressure in chamber 30 and in the low-pressure receiver 40 to which it is connected. The amount of low pressure is adjusted to apply an upward force on the main piston 29 of slightly more than one-half the weight of the piston and its rod 26, crown sheave 21 and frame 24, so that a slight tension is maintained in rope 18. On the downstroke essentially free fall of the tool occurs. All valves are in the same position as in the previous case.

(7) *Mid downstroke.*—In this position, the piston 29 is just below intake cutoff position. When the piston passes intake cutoff position, pilot valve B opens, but air pressure supplied by pilot valve B to pilot valve D is blocked at port 81 because the exhaust valve is still open.

(8) *Late downstroke.*—In this portion of the cycle, the piston 29 is in "near-bottom" exhaust cutoff (i. e. closing)

position, at which point pilot valve C is opened by cam 58b so that air pressure flows through port 91 into actuating chamber 93 of exhaust valve 33, tripping the exhaust valve into closed position; and at the same time uncovering port 81 of pilot valve D, so that intake valve 32 is opened, pressure is built up below main piston 29 and a new upstroke commences.

Air pressure in chamber 30 and the points at which the pilot valves and the intake and exhaust valves are closed, during the above-described operating cycle of piston 29, are shown graphically in Figure 5, which is schematic and not necessarily to scale.

Although the invention has been described as operated by compressed air, other gases, such as steam can be used satisfactorily, and the claims are to be construed to cover such equivalents.

Furthermore, although I prefer, for safety reasons, to employ main control valve A in my air-pilot control circuit, this valve can, if desired, be omitted and the position of pilot valve B below its cutoff point on cam 58a, with the main piston 29 in bottom position, can be relied on to stop reciprocation of the piston. Piston 29 can then be started by merely sliding pilot valve B above its cutoff position.

Furthermore, although pressure fluid is shown in Figure 2 as the medium through which the pilot means (valves B, C, and D) control the master (intake and exhaust) valves, it will readily be seen that, in its broad aspect, the invention is equally applicable to the employment of other equivalent media, such, for example, as electrical means in which electrical switches are substituted for the pilot valves and serve to control the master valves through electrically-operated solenoids. Such an alternative embodiment is shown in Figure 6.

In Figure 6, which shows the second embodiment of the invention, the electrical pilot control circuit, which is substituted for the pneumatic pilot control circuit of Figure 2, consists of an electrical power source 150, main control switch A', intake cutoff control switch B', exhaust cutoff control switch C', exhaust-valve actuated switch D', intake valve opening solenoids 103, exhaust valve closing solenoid 193, and the necessary connecting lines as hereinafter described.

Intake cutoff control switch B' consists of a conducting bar 158a', which is connected to main control switch A', and of slidably mounted contactor 164. Conducting bar 158a' is mounted on piston rod 26 and corresponds to cam surface 58a' of the first embodiment (Figure 2). Accordingly electrical contact exists between conducting bar 158a' and contactor 164 when piston 29 is below its intake cutoff point as predetermined by the setting of slidably contactor 164.

Exhaust cutoff control switch C' consists of a conducting bar 158b' which is connected to main control switch A', and of contactor 174. Conducting bar 158b' is mounted on piston rod 26 and corresponds to cam surface 58b' of the first embodiment (Figure 2). Accordingly electrical contact exists between conducting bar 158b' and contactor 174 when piston 29 is below its exhaust cutoff point.

Exhaust valve actuated switch D' consists of a contactor 184 connected by line 166 to contactor 164 of switch B', and of contact plate 185 connected by line 186 to intake valve solenoid 203. Contact plate 185 is mounted on stem 194 of exhaust valve 133, so that plate 185 establishes electrical connection with contactor 164 when the exhaust valve is closed and interrupts this connection when the exhaust valve is open.

Intake valve 132 is spring-closed, solenoid-opened. When electrical potential is applied to the solenoid 203 through line 186, armature 107 connected to valve stem 204 is pulled in, thus opening valve 132 and compressing spring 108. The electrical circuit is closed by line 187 from solenoid 203 to power supply 150.

Exhaust valve 133 is spring-opened, solenoid-closed.

When electrical potential is applied to the solenoid 193 through line 176 from contactor 174 of switch C', armature 197 connected to valve stem 194 is pulled in, thus closing valve 133 and compressing spring 198. The electrical circuit is closed by line 177 from solenoid 193 to power supply 150.

Operation of this electrical-pilot control is analogous to the air-pilot control of the first embodiment: At the bottom of the stroke, switches B' and C' are closed; and since the closed switch C' holds exhaust valve 133 closed, switch D' is also closed. The series-connected switches B' and D' being closed, the intake valve 132 is held open. Air pressure in main cylinder chamber 30 causes main piston 29 to rise. When the exhaust cutoff point is passed, switch C' opens, but the exhaust valve is kept closed by the high pressure in main cylinder chamber 30. When the intake cutoff point is passed, switch B' opens, causing inlet valve 132 to close. Air in the now-sealed-off main cylinder chamber 30 expands, and when the air pressure drops below a predetermined level, exhaust valve 133 opens, thus opening switch D'. Soon thereafter, piston 29 reaches the top of its stroke and begins to fall. When the intake cutoff point is passed, switch B' closes, but current through the intake solenoid 203 still being interrupted at switch D', the intake valve remains closed. When the piston passes the exhaust cutoff point, switch C' closes, thus closing the exhaust valve. This causes switch D' to close, whereupon intake valve 132 opens.

Having now described and illustrated two forms of the invention it is to be understood that the invention is not to be limited to the specific form or arrangement of parts herein described and shown.

I claim:

1. In a control for a pneumatic cable-tool drill having: a bit; pneumatic spudding means having a cylinder-piston assembly supporting said bit to raise and drop said bit; a piston and a pressure chamber in said cylinder-piston assembly, said chamber having associated with it a fluid-pressure intake port and an exhaust port; an intake valve to open and close said intake port; an exhaust valve to open and close said exhaust port; and means operatively connected to said exhaust valve to open and close said exhaust valve; a combination therewith of: means adapted to open and close said intake valve, said last-mentioned means comprising: first and second valve-control means operatively connected to said intake valve each having port-closing and port-opening positions to effect closing and opening of said intake valve; piston-position responsive means connected to and operated by said piston to actuate said first valve-control means to assume a port-closing position when the piston reaches a predetermined intake cut-off position on its bit-raising stroke; exhaust-valve-position responsive means connected to and operated by said exhaust valve to actuate said second control means to assume a port-closing position when said exhaust valve is in open position and to assume a port-opening position when said exhaust valve is in closed position; and interlock means connecting said first and second control means, said interlock means providing for independent operation of said first and second control means with respect to their port-closing function to cut off intake of fluid pressure at said cut-off position of the piston on its bit-raising stroke and to cut off intake of fluid pressure when the exhaust valve is open on the bit-lowering stroke of the piston, and providing dependent operation of said first and second control means with respect to their port-opening function to

effect fluid-pressure intake only during the portion of the bit-raising stroke in advance of said cut-off position of the piston and when said exhaust valve is closed.

2. A control for a pneumatic cable-tool drill according to claim 1, further characterized by the fact that the intake valve is a fluid-pressure-actuated power-opening valve, and that the interlock between the first and second control means is a series fluid-pressure circuit.

3. A control for a pneumatic cable-tool drill according to claim 2, further characterized by the fact that the first and second control means comprises fluid-pressure valves actuated by movement of the piston and by movement of the exhaust valve respectively.

4. A control for a pneumatic cable-tool drill according to claim 1, further characterized by the fact that the intake valve is an electrically-actuated power-opening valve having a pilot electrical circuit adapted to open said port, and that the interlock between the first and second control means is a series electrical circuit.

5. A control for a pneumatic cable-tool drill according to claim 4, further characterized by the fact that the first and second control means comprises pilot electrical switches actuated by movement of the piston and by movement of the exhaust valve respectively.

6. In a control for a pneumatic cable-tool drill having: a bit; pneumatic spudding means having a cylinder-piston assembly supporting said bit to raise and drop said bit; a piston and a pressure chamber in said cylinder-piston assembly, said chamber having associated with it a fluid-pressure intake port and an exhaust port; an intake valve to open and close said intake port; an exhaust valve to open and close said exhaust port; and means to open and close said intake valve; the combination therewith of: means adapted to open and close said exhaust valve, said last-mentioned means comprises: first control means operatively connected to said exhaust valve having port-closing and port-opening positions to effect closing and opening of said exhaust valve; piston-position responsive means connected to and operated by said piston to actuate said first control means to assume a port-closing position when the piston reaches a position in advance of its normal position of reversal from a bit-lowering to a bit-raising stroke; and second fluid-pressure responsive control means associated with the exhaust valve, said second control means being directly actuated by fluid pressure in said chamber and including a fluid-pressure operating surface associated with said exhaust valve and dimensioned and biased by the fluid pressure in said chamber to close said exhaust valve when pressure in said chamber is above a predetermined value.

7. A control for a pneumatic cable-tool drill according to claim 6, further characterized by the fact that the first control means comprises a fluid-pressure pilot valve actuated by movement of the piston.

8. A control for a pneumatic cable-tool drill according to claim 6, further characterized by the fact that the first control means comprises a pilot electrical switch actuated by movement of the piston.
